UNITED STATES PATENT OFFICE.

PETER E. WEILERT, OF KANSAS CITY, MISSOURI.

OIL-BURNING APPARATUS.

Application filed June 16, 1923. Serial No. 645,845.

To all whom it may concern:

Be it known that I, PETER E. WEILERT, a citizen of the United States, residing at Kansas City, in the county of Jackson and State of Missouri, have invented certain new and useful Improvements in Oil-Burning Apparatus, of which the following is a specification.

My invention relates, generally, to oil burning apparatus adapted for installation in connection with domestic and industrial furnaces, and more particularly to means for automatically cutting off the flow of oil in the event that the supply of air which is combined with said oil to form a highly combustible mixture should be interrupted from any cause, thereby avoiding the danger arising from overflow of the oil.

In order that the invention may be fully understood, reference will now be had to the accompanying drawings, in which:

Fig. 1 is a side elevation of the apparatus partly in section.

Fig. 2 is an enlarged broken vertical section showing the important features of the invention.

Fig. 3 is an irregular vertical cross section on line III—III of Fig. 1.

Fig. 4 is a broken irregular longitudinal section on line IV—IV of Fig. 2.

Fig. 5 is a broken side elevation, partly in section, of a modified form of the invention.

Fig. 6 is a broken rear elevation of the modified form.

Referring now in detail to the various parts disclosed by Figs. 1 to 4, inclusive, 2 designates an air pipe connected at its intake end to a housing 4, and at its opposite end to a nozzle 6, discharging into a retort 8, or any other suitable burner for a combustible mixture of air and fuel oil.

10 designates any suitable air current creating mechanism, shown in the present instance in the form of a blower connected to the housing 4 and having an air intake opening 12 and a discharge opening 14, which latter is, preferably, in axial alignment with the air pipe 2 as more clearly disclosed by Fig. 2.

16 designates a vane or any other suitable member adapted to be actuated by the air current created by the blower 10. Said vane 16 is fixedly connected to a rock shaft 18 from which it is suspended in such manner as to normally close the discharge opening

14. The rock shaft 18 is journaled in opposite sides of the housing 4 and provided with a fixedly-mounted eccentric 20 upon which a counterweight 22 rests. The counterweight 22 is mounted upon one end of a lever 24 fulcrumed at its opposite end upon a bracket 26 clamped upon a suitable support such as a manually-controlled valve 28 connected to an oil feed pipe 30 leading from a suitable source of supply, not shown, and connected to an oil jet 32 extending centrally through the nozzle 6 and adapted to discharge into the retort 8. The lever 24 has a pin-and-slot connection 34 with a valve 36, which is rendered self-closing through the intermediary of counterweight 22. Said valve 36 is connected to the oil pipe 30 adjacent to the valve 28, which has a hand wheel 38 whereby it may be opened and closed.

40 designates a motor, preferably of the electric type, mounted upon a base 42 and provided with a drive shaft 44 upon which the rotor 46 of the blower 10 is fixedly mounted.

In practice the manually-controlled valve 28 is opened sufficiently to permit the desired quantity of oil to flow through the pipe 30 to the oil jet 32 from which it is discharged into the retort 8. The motor 40 is also started to drive the blower which forces a current of air through the pipe 2 to the air nozzle 6 from which it discharges with sufficient velocity to convert the oil 90 discharged from the oil jet 32 into spray, the air becoming thoroughly mixed with said spray and forming a highly combustible mixture which may be ignited by any suitable means.

The current of air created by the blower 10 swings the vane 16 upwardly to the dotted position disclosed by Fig. 2, causing said vane 16 to rock the shaft 18, which in turn rocks the eccentric 20, so that the high radius thereof will engage the counterweight 22 and raise the same and the lever 24 to the dotted line position, thereby opening the valve 36 and allowing the oil to flow through the pipe 30 to the oil jet 32, as above stated. Should the motor 40 stop from any cause and thus fail to actuate the blower 10 the vane 16 immediately moves downwardly by the force of gravity to the full line position disclosed by Fig. 2, 110 causing the high radius of the eccentric 20 to pass out of engagement with the counter-

weight 22 and thereby permitting the same and the lever 24 to automatically close the valve 36 and shut off the flow of oil to the jet 32. By thus automatically cutting off the flow of oil when there is no air current to form a highly combustible mixture the danger arising from an overflow of oil is obviated.

In the form disclosed by Figs. 5 and 6 the principle is the same as that disclosed by Figs. 1 to 4, inclusive, as evidenced by corresponding reference numerals with exponents "a," the chief difference being that the vane 16^a is arranged at the intake opening 12^a of the blower 10^a instead of at the discharge opening. When the blower 10^a is at rest the vane 16^a normally stands in open position as disclosed by Fig. 6, but is drawn inwardly against the intake 12^a by the current of air created by the blower when the same is in operation. The vane 16^a is fixed to a shaft 50 mounted in bearings 52 and provided with a fixedly mounted crank 54, connected to another crank 56 through the intermediacy of a connecting rod 58. The crank 56 is fixed upon the rock shaft 18^a carrying the eccentric 20^a upon which the counterweight 22^a rests. When the blower 10^a is in operation the air current created thereby carries the vane 16^a across the intake 12^a, causing said vane 16^a, through the intermediacy of the intervening mechanism, to open the valve 36^a and permit oil to flow to the retort through the oil pipe 30^a. When the blower 10^a is at rest the vane 16^a is carried by the force of gravity away from the

intake 12^a and permits the counterweight 22^a and the lever 24^a to close the valve 36^a. The vane 16^a has a plurality of openings 60 through which the air current passes when 40 the blower is in operation, and draws said vane 16^a across the intake 12^a.

While it is preferable to place the vane either adjacent to the intake or discharge opening of the blower, owing to the fact 45 that the air current is strongest at these points, it is to be understood that the vane, or its equivalent, may be located at any suitable point where it will be acted upon by the air current and effect the opening of the 50 self-closing valve.

Having thus described my invention, what I claim and desire to secure by Letters Patent, is:

In combination with a burner, an oil pipe 55 for supplying said burner with fuel oil, an air pipe for supplying said burner with air, a vane controlled by the air passing through said air pipe, a rock shaft on which said vane is fixedly mounted, an eccentric fixedly 60 mounted on said rock shaft, a valve for controlling the flow of oil through the oil pipe, a lever for opening and closing said valve, and a counterweight fixed to said lever to actuate the same and resting on said eccentric in order to be actuated thereby.

In testimony whereof I affix my signature, in the presence of two witnesses.

PETER E. WEILERT.
